UNITED STATES PATENT OFFICE.

ALVIN O. CARMAN, OF POTTERVILLE, MICHIGAN.

SELF-BINDING HARVESTER.

SPECIFICATION forming part of Letters Patent No. 339,145, dated April 6, 1886.

Application filed November 3, 1884. Serial No. 147,087. (No model.)

To all whom it may concern:

Be it known that I, ALVIN O. CARMAN, of Potterville, in the county of Eaton and State of Michigan, have invented certain new and useful Improvements in Self-Binding Harvesters; and I do hereby declare the following to be a full, clear, and exact description of the invention, such as will enable others skilled in the art to which it appertains to make and to use the same.

My invention relates to an improvement in self-binding harvesters, the object of the same being to provide improved mechanism for transmitting power from the driving-shaft to the binder and from the binder to the packer-shaft; a further object being to provide an improved tripping device; a further object being to provide improved ejecting mechanism.

With these ends in view my invention consists in certain features of construction and combinations of parts, as will be hereinafter described, and pointed out in the claims.

In the accompanying drawings, Figure 1 is a vertical transverse section of a portion of a harvester embodying my invention. Fig. 2 is a plan view. Fig. 3 is a view in end elevation; Fig. 4, a view in side elevation; and Fig. 5 is a detached view.

A represents the main frame of the reaper, to the outer end of which the supporting-frame of the binder, packer, and ejector mechanism is secured, the said supporting-frame consisting, preferably, of four uprights, a , a' , a^2 , and a^3 , the two latter being somewhat higher than the two former, and connected by a top rail, B. a and a' are connected by a top rail, b , and the uprights a' a^3 and a a^2 are connected by cross-girders b' and b^2 b^3 , respectively. Two intermediate cross-girders, C c , are secured at one end to the rail B, and extend from thence downwardly to the plane of the girders b' b^2 , thence outwardly to the rail b , to which they are secured, and from thence project outwardly and terminate in bearings c' , for the ejector-shaft c^2 .

D is the binder-actuating shaft. It is journaled in suitable bearings, d , secured to the girders b' b^2 , and also has bearings d' on the intermediate girders, C c . The front end of D is provided with a spur-wheel, E, mounted

loosely thereon, and with a combined cam and mutilated gear-wheel, e , secured rigidly thereon in juxtaposition to the wheel E. Motion is imparted to the spur-wheel E by a pinion, F, rigidly secured on a short shaft, f , journaled at one end to the upright a or cross-girder b^2 and at the other end in a bracket-arm, b^4 , secured to the upright a . The pinion F is driven by suitable gear connecting it with the main driving-shaft. (Not shown.) The front side of the rim of wheel E is provided with ratchet-notches e' , and a dog, f' , actuated by spring f^6 , is secured to the rear side of the rim of wheel e in such a position that it engages the notches e' when in its normal position, and thereby locks the wheel e to E, causing said wheels to rotate together, and hence causing the shaft D to rotate. The dog f' is, however, forced out of engagement with the wheel E, while the grain is gathering and being packed for a bundle, by means of an arm or finger, f^2 , rigidly secured on the front end of the trip-shaft G, the said finger f^2 being adapted to rest between the dog and rim of the wheel E, and is held in this position by the tension of a spring, f^3 , on the said shaft G. The end of the finger f^2 is adapted to engage a shoulder, f^4 , on the dog f' , when in position, to hold dog out of engagement with the wheel E, and thereby prevent any displacement of the wheel e or shaft D in a forwardly rotary motion.

The trip-shaft G, above referred to, is journaled in suitable bearings secured to the upright a^2 and to an inwardly-extending arm, g , the latter being secured to the side of the knotter-frame H. The shaft G is further provided on its rear end with a downwardly and outwardly extending trip-finger, g' , the purpose of which will hereinafter more plainly appear. An inclined table, I, extends upwardly from the reaper-platform to a position beneath the trip-finger g' , the lower end of the trip-finger resting on or near said apron.

The packer-shaft K is journaled in suitable bearings secured to the upright a^2 and the intermediate cross-girders, C c , a short distance below the top rail B. The shaft K is provided near its forward end with a pinion, k , adapted to engage the spur-wheel E, said pinion being

loosely mounted on the shaft and provided with notches on the front end of its hub, adapted to engage the clutch k' . The clutch k' is allowed a sliding motion on the shaft K, and 5 caused to rotate with the shaft by means of a feather and groove or other suitable device, and is provided with an annular groove, k^2 , adapted to receive the branches of the operating lever or arm k^3 . The latter is pivoted 10 to the end of an arm, i , rigidly secured to the top rail B, and extending forwardly and outwardly to a point in front of the wheel e , as shown. The clutch k' is forced into engagement with the pinion k by a spring, k^4 , on the 15 front end of shaft K, and is forced and held out of engagement therewith by a lug, k^5 , on the operating-arm k^3 , which engages the front rim of the wheel e . At one point the said rim is cut away, forming a notch, k^6 , said notch 20 having an abrupt shoulder on one side and a gradual incline on the other, whereby the lug k^5 , when in the notch, prevents the wheel from displacement in a backward rotary motion, but allows it to turn freely in a forward direction. When the lug k^5 is in the notch k^6 , the 25 clutch is in engagement with the pinion-hub. The shaft K is further provided with a double crank, L, about midway between the intermediate girders, C e, to which crank the packers 30 l are pivoted. A T-shaped standard or bracket, K^5 , (this bracket has been shown detached on Sheet 1,) is secured to the knotter-frame H at a point corresponding with the double crank, the ends of the cross-bar of said bracket 35 forming bearings for the ends of connecting-links l' , pivotally secured thereto and to the packers l . The packers l are provided with bows l^2 on their backs, to guide the grain smoothly beneath the arm when it is down. 40 The knotter-frame H, referred to above, is supported at each end by the girders C e, and is located below the binder-actuating shaft D. The knotter itself forms no part of my present invention, and is not shown. It may be 45 of any approved construction consistent with the arrangement of parts shown, and is located within the frame H. The compressor-arm shaft M is journaled in suitable bearings, m m' , the former secured to the upright a and 50 the latter to the frame H. The compressor-arm m^2 is rigidly secured to the rear end of the shaft M, and extends downwardly in close proximity to the floor of the binder. The forward end of the shaft M is provided with a 55 rigid collar, m^3 , having a projecting lug or arm, m^4 , secured thereto. Said shaft M is also provided with a loose crank, m^5 , located in close proximity to the collar m^3 , and with a spring, m^6 , the tension of which tends to force 60 the arm m^2 away from the grain into elevated adjustment. The crank m^5 is connected with the lower end of the operating-lever N by a rod, n . The lever N is pivotally secured to the arm i , and is provided at or near its central portion 65 with a stud, n' , carrying an anti-friction roller, n^2 , adapted to engage the cam-groove n^3 in the front face of the wheel e . The portion of

the groove n^3 lying nearest the center of the wheel e forces the operating-lever outwardly, and leaves the shaft M free to be rotated by the 70 tension of the spring m^6 , but when the lever engages the portion of the groove n^3 lying farthest from the center of e the shaft M, being now locked to the crank m^5 by the arm m^4 , coming in contact with the rod n , will be rotated in the opposite direction against the tension of the spring m^6 , thereby depressing the compressor-arm m^2 , and holding the same in a depressed position until the irregular portion of the groove is again reached by the 80 lever. The needle-shaft O is journaled in suitable bearings secured to the cross-girder b^3 and to a support, o. The shaft O is provided with the binder-arm or needle o' , rigidly secured to its rear end, and with the crank o^3 , 85 rigidly secured to its forward end. A crank, o^3 rigidly secured on the forward end of the binder-shaft D, is connected with the crank o^2 by a rod, o^4 , in such a manner that a revolution of the shaft D will raise the needle to a 90 point beneath the frame H, and return the same to its depressed position. The ejector-shaft c^2 , as hereinbefore stated, is journaled in the outer ends of the intermediate girders, C e. It is provided with a pair of large sprocket-wheels, P, rigidly secured thereon between its bearings, and with a small sprocket-wheel, p , rigidly secured on its forward end. Motion is communicated to the shaft c^2 from a sprocket-wheel, p' , rigidly secured on the binder-shaft 100 D, and connected with the wheel p by a sprocket-chain, p^2 . Two sprocket-pulleys, q , are mounted on stub-axles or studs p^3 , set in brackets p^4 , secured to the inner side of the knotter-frame H in positions corresponding with the 105 large sprocket-wheels P. The ejector-arms R are pivotally secured to corresponding links on the two endless chains Q, which pass about the wheels P and pulleys q , and said arms R are further secured to the chains by 110 curved links r , which are pivotally secured to the arms R and to links of the chains located in the rear of the arms R. By the above construction the arms on the chains Q are free to adapt themselves to the curve of the wheels, 115 and at the same time they are braced in a position at right angles to the chains while they travel from the binder-floor outwardly, and the arms R, as they pass from the binder-floor outwardly, are in close proximity to the floor 120 J. Said arms R, furthermore, occupy such a position on the chains that they come in contact with the inner side of the bundle at the moment the knot is tied, and slide the same outwardly off the floor J. 125 The combined operation of the parts herein described is as follows: Suppose the cam k^5 on the clutch-operating arm k^3 to be in the notch k^6 , and hence the clutch k' in engagement with the pinion k , and suppose the trip-finger g' to be depressed, and hence the dog-operating arm or finger f^2 in position between the wheel E and dog f' , thereby holding the latter out of engagement with the ratchet-

notches on E, leaving E free to rotate. As E is loosely mounted on the shaft D, the binder and ejector mechanism will remain quiet, and the packer-arms, driven by the wheel E, will 5 operate, gathering the grain beneath the finger g'. When sufficient grain has gathered beneath said finger to rotate the shaft G and release the dog f' from the arm f², the said dog will spring into engagement with one of the 10 notches e', thereby locking the wheel e to the wheel E and causing it to rotate therewith. This starts the binder-shaft, needle-shaft, and ejector mechanism, and at the same time slides the lug k⁵ out of the notch k⁶, thereby 15 releasing the clutch k' from the pinion k and stopping the packer-shaft. The first half-revolution of the shaft D elevates the binder arm or needle o', separating the gavel, forcing it against the compressor-arm m², and carrying 20 the cord around it to the knotter. The second half-revolution of shaft D returns the needle to its depressed position, ties the knot, releases the compressor-arm m², and conveys the bundle, by means of the ejector-arms, 25 outwardly off the machine. At the moment the revolution of D is completed the lug k⁵ again falls into the notch k⁶, the clutch engages the pinion k, the arm f² releases the dog f' from the wheel E, the binder stops, and the 30 packers begin to operate, as before noted.

It will be observed that by the above construction the packers are automatically stopped while the binder and ejector mechanism is in motion, and, vice versa, that the 35 compressor-arm is positively forced downward and held in contact with the gavel, that the ejector mechanism slides the bundle off the machine without any tendency to roll it, and that the dog and clutch operating devices 40 serve at the same time to lock the binder-shaft against displacement, thus reducing the number of parts and simplifying the general construction.

It is evident that slight changes may be 45 made in the form and arrangement of the several parts described without departing from the spirit and scope of my invention; hence I do not wish to be understood as limiting myself strictly to the construction herein set forth.

I am aware that it is not new to provide 50 endless chains with carrying-arms, the latter being pivotally braced on said chains, and hence I make no claim to these parts, separately considered.

Having fully described my invention, what 55 I claim as new, and desire to secure by Letters Patent, is—

1. In a self-binder, the combination, with the binder-actuating shaft, of a spur-wheel 60 mounted loosely thereon, a cam-wheel rigidly secured thereon, a dog pivotally secured to the inner face of the cam-wheel and adapted to engage teeth on the adjacent face of the spur-wheel, and devices, substantially as described, for holding the dog out of contact with the spur-wheel.

2. In a self-binder, the combination, with

the binder-actuating shaft, of a combined spur and ratchet wheel mounted loosely thereon, a cam-wheel for operating the knotter, the binder-arm and ejector mounted rigidly thereon, and a dog secured to the cam-wheel adapted to engage the ratchet-notches on the spur-wheel, thereby causing the wheels to rotate together, substantially as set forth. 70

3. In a self-binder, the combination, with the binder-actuating shaft having a spur-wheel provided with ratchet-notches mounted loosely thereon, and a cam-wheel for operating the knotter, binder-arm, and ejector mounted 80 rigidly thereon, of a dog secured to the cam-wheel and adapted to engage the ratchet-notches on the spur-wheel, and a releasing-finger secured on the trip-shaft adapted to hold the dog out of contact with the spur-wheel 85 while the gavel is forming, substantially as set forth.

4. In a self-binder, the combination, with the binder-actuating shaft having a spur-wheel and a cam-wheel mounted thereon, the former 90 loosely and the latter rigidly secured on the binder-shaft, devices, substantially as described, for locking the spur-wheel to the shaft, and the packer-shaft geared with the spur-wheel and provided with a clutch, of a clutch-operating arm adapted to engage the face of the cam-wheel for the purpose of throwing the packer-shaft out of gear while the binder is in motion, substantially as set forth.

5. In a self-binder, the combination, with 100 the binder-shaft having the spur-wheel mounted loosely thereon and the cam-wheel mounted rigidly thereon, and the packer-shaft provided with a loose pinion geared with the said spur-wheel and with a clutch, of the dog, 105 its releasing-arm, a shaft, and a trip-finger for operating the releasing-arm, and the clutch-operating arm, whereby the packer mechanism and the binder mechanism are alternately set in motion and stopped, substantially as set 110 forth.

6. In a self-binder, the combination, with a cam-wheel rigidly secured on the binder-shaft, 115 said cam-wheel having a shouldered dog secured on one side and a notch formed on the opposite side, of a dog-releasing finger and a clutch-operating lever adapted to engage the shoulder and notch, respectively, thereby locking the cam-wheel against displacement, substantially as set forth. 120

7. In a self-binder, the combination, with a cam-wheel rigidly mounted on the binder-shaft, having a notch on the side of its rim, a spur-wheel loosely mounted on said shaft, and a packer-shaft provided with a loose pinion 125 gearing with the spur-wheel, of a spring-actuated clutch secured on the packer-shaft, and a clutch-operating arm provided with a lug adapted to engage the notch on the cam-wheel, thereby locking the loose pinion to the packer-shaft and causing the shaft to rotate, substantially as set forth. 130

8. In a self-binder, the combination, with a cam-wheel rigidly secured on the binder-shaft,

the compressor-arm, compressor-arm shaft, and the spring for raising the compressor-arm, of the crank loosely mounted on said shaft, the rigid collar having a projecting arm, a lever adapted to engage a cam-groove on said cam-wheel, and a rod connecting the lever and the crank, all of the above parts combined operating substantially as set forth.

9. In a self-binding harvester, the combination, with a binder-actuating shaft, a spur-wheel mounted loosely thereon, a cam-wheel rigidly secured thereon, and a dog secured to the rigid wheel and adapted to engage the adjacent face of the loose wheel, of a chain-driving wheel rigidly secured on the binder-actu-

ating shaft, the shaft c^2 , having chain-wheels thereon, the wheels q and the chains Q , the ejector-arms pivotally secured to the chains, and a packer-shaft and packers, the parts being arranged substantially as described, where-
by when the packers are operating the binding mechanism and ejectors are at rest, substantially as set forth.

In testimony whereof I have signed this specification in the presence of two subscr-
ing witnesses.

ALVIN O. CARMAN.
